DE WITT T. LYON

RADIATOR

Filed Oct. 24, 1921

UNITED STATES PATENT OFFICE.

DE WITT T. LYON, OF CHICAGO, ILLINOIS, ASSIGNOR OF ONE-HALF TO BABET R. H.
LYON, OF CHICAGO, ILLINOIS.

RADIATOR.

Application filed October 24, 1921. Serial No. 509,826.

To all whom it may concern:

Be it known that I, DE WITT TAYLOR LYON, a citizen of the United States, and a resident of Chicago, in the county of Cook and State of Illinois, have invented a new and useful Improvement in Radiators, of which the following is a full, clear, and exact description.

My invention relates to improvements in radiators, and it consists in the combinations, constructions, and arrangements herein described and claimed.

An object of my invention is to provide an improvement over that form of the device shown in my prior application for patent, Serial No. 430,321, filed December 13, 1920. In said application there was disclosed a radiator composed of a plurality of sections, each section comprising an upper and a lower header portion with pipes connecting said headers, the upper and lower headers being so formed as to interlock with adjacent headers, thereby forming a self-centering construction which makes the units easy to assemble and also aids in preventing the units from getting out of alignment. In my present device the headers have offset compartments communicating therewith, each of said compartments having an opening therein adapted to receive an end of a connecting pipe. With this construction the connecting nipples can be readily turned by means of a wrench without the necessity of tipping or moving the sections.

A further object of my invention is to provide a device of the type described which is simple in construction, easy to assemble, and not likely to get out of order easily.

Other objects and advantages will appear in the following specification, and the novel features of the invention will be particularly pointed out in the appended claims.

My invention is illustrated in the accompanying drawings forming part of this application, in which—

Figure 1 is a side elevation of the device,

Figure 2 is a section along the line 2—2 of Figure 1,

Figure 3 is a horizontal section of a modified form of the device,

Figure 4 is a horizontal section of another modified form of the device, and

Figure 5 is a horizontal section of still another modified form of the device.

In carrying out my invention, I provide headers 1 and 2 communicating with each other by means of pipes 3. As clearly shown in Figures 1 and 2 the headers 1 and 2 have lateral extensions or compartments 4 and 5 which have openings therein. The headers 1 and 2 are adapted to be placed in rows so that the compartments 4 and 5 are adjacent one another. A pipe or coupling 6 having a nut integral therewith is screwed into the aligned openings of the compartments adjacent one another. It will be seen that a series of headers can be placed side by side and thus provide a radiator of any desired length. It will be understood that the compartments in the lower headers are joined together by the pipes 6 and that the compartments in the upper headers are also joined together by other pipes 6. The headers at each end of the row are connected to a source of steam supply (not shown). The steam will thereupon flow in a circuitous path from header to header, thus effectually warming the pipes 3. The headers can be easily and readily assembled or disassembled by merely screwing or unscrewing the pipes 6. The pipes 6, as will be noted, are disposed on the sides of the headers 1 and 2 and can therefore be readily operated. This permits the different headers to be taken apart by a wrench (not shown) without the necessity of moving the headers at all.

In Figure 2, I show the headers as parallelogramic in shape and they therefore can be readily assembled, and when assembled, form a straight row or line. The pipes 3 are staggered with respect to each other, thus causing the air flowing therebetween to take a circuitous path and be readily warmed thereby.

In Figures 3, 4, and 5, I show modified forms of the device. These forms are identical with respect to the form shown in Figures 1 and 2, and the same reference numerals describing the preferred form will be used in these forms. In the form shown in Figure 3, the headers are V-shaped and thus are prevented from lateral movement with each other when assembled.

In the form shown in Figure 4, each of the headers resembles a triangle and also interlock with each other when assembled. The form shown in Figure 5 has its head-

ers in the shape of a trapezoid and are prevented from lateral movement with each other in substantially the same manner as the forms shown in Figures 3 and 4.

From the foregoing description of the various parts of the device, the operation thereof may be readily understood. In assembling the different headers, the pipes 6 are inserted in the openings in the compartments 4 or 5, as the case may be, and are then screwed into the openings in the adjacent compartments carried by the adjoining headers. This construction provides a device which is readily assembled since the pipes 6 are easily accessible from the sides of the radiator and the latter can therefore be manipulated without moving the entire device.

I claim:

1. A radiator comprising a plurality of sections, each of said sections having a lower and an upper header, the abutting sides of said headers being fashioned so as to prevent lateral movement of said headers with respect to each other when said headers are assembled, a plurality of pipes disposed between each upper and lower header, said pipes placing said headers in communication with each other, laterally extending compartments carried by said headers, and connecting pipes adapted to secure the adjacent compartments together, whereby the various sections are held together as a unit. 30

2. A radiator comprising a plurality of sections, the abutting sides of said sections being fashioned so as to prevent lateral movement of said sections with respect to each other when said sections are assembled laterally extending compartments carried by said sections and communicating therewith, and pipes connecting said compartments, whereby the sections are prevented from longitudinal movement with respect to each other and are held together as a unit. 35

3. A radiator comprising a plurality of sections, each section having an upper and a lower header, pipes connecting said upper and lower headers together, the contiguous walls of the adjacent headers having oblique angles, whereby one header has a portion fitting within the recess of the adjacent header, and means for connecting adjacent sections together. 40

DE WITT T. LYON.
